CLAIM

The ornamental design for a motorized abrasive cue tip shaper, as shown and described.

DESCRIPTION

FIG. 1 is a perspective view of the motorized abrasive cue tip shaper, showing my new design;

FIG. 2 is a front elevational view thereof with the cap portion shown removed for purposes of disclosure;

FIG. 3 is a bottom plan view thereof;

FIG. 4 is a top plan view thereof;

FIG. 5 is an elevational view of one side, the opposite side being a mirror image thereof; and,

FIG. 6 is an enlarged fragmentary sectional view of the abrasive portion taken along the line 6—6 of FIG. 4.

FIG. 1.

FIG. 3.

FIG. 4.

FIG. 2.

FIG. 5.

FIG. 6.
